CLAIM

The ornamental design for telephone instrument base, as shown and described.

DESCRIPTION

FIG. 1 is front, top and right side perspective view of a telephone instrument base showing our new design;

FIG. 2 is a rear elevational view thereof;

FIG. 3 is a left side elevational view thereof, the side opposite being substantially a mirror image; and

FIG. 4 is a bottom plan view thereof.

*Fig.1.**Fig.2.**Fig. 3.**Fig. 4.*
